US0D1010104S

(12) United States Design Patent (10) Patent No.: US D1,010,104 S
(45) Date of Patent: * Jan. 2, 2024

(54) HICCUP RELIEVING APPARATUS

(71) Applicants: Victor W. Fehlberg, Longmont, CO (US); Ali Seifi, San Antonio, TX (US)

(72) Inventors: Victor W. Fehlberg, Longmont, CO (US); Ali Seifi, San Antonio, TX (US)

(73) Assignee: Higher Innovations, Inc., Longmont, CO (US)

() Term: 15 Years

(21) Appl. No.: 29/729,123

(22) Filed: Mar. 24, 2020

Related U.S. Application Data

(63) Continuation of application No. 16/802,432, filed on Feb. 26, 2020.

(57) CLAIM

The ornamental design for a hiccup relieving apparatus, as shown and described.

DESCRIPTION

FIG. 4 is a right side view thereof.

FIG. 5 is a back view thereof.

FIG. 6 is a front view thereof.

FIG. 7 is a top view thereof; and,

FIG. 8 is a bottom view thereof.

1 Claim, 2 Drawing Sheets
